UNITED STATES PATENT OFFICE.

ERNEST GOODWIN, OF EAST LIVERPOOL, OHIO, ASSIGNOR TO THE EDWIN M. KNOWLES CHINA CO., OF EAST LIVERPOOL, OHIO, A CORPORATION OF WEST VIRGINIA.

DESIGN FOR A COVERED DISH OR SIMILAR ARTICLE.

Application filed September 3, 1925. Serial No. 14,703. Term of patent 7 years.

To all whom it may concern:

Be it known that I, ERNEST GOODWIN, a citizen of the United States, residing at East Liverpool, in the county of Columbiana and State of Ohio, have invented a new, original, and ornamental Design for a Covered Dish or Similar Article, of which the following is a specification, reference being had to the accompanying drawing, forming part thereof.

I claim:

The ornamental design for a covered dish or similar article, as shown.

ERNEST GOODWIN.
